UNITED STATES PATENT OFFICE.

FREDERICK L. MURDOCK, OF MERIDEN, CONNECTICUT.

ARTIFICIAL DENTURE.

1,277,245.

Specification of Letters Patent. Patented Aug. 27, 1918.

Application filed June 7, 1918. Serial No. 238,651.

To all whom it may concern:

Be it known that I, FREDERICK L. MURDOCK, a citizen of the United States, residing at Meriden, in the county of New Haven 5 and State of Connecticut, have invented a new and useful Improvement in Artificial Dentures; and I do hereby declare the following, when taken in connection with the accompanying drawings and the characters 10 of reference marked thereon, to be a full, clear, and exact description of the same, and which said drawings constitute part of this application, and represent, in—

Figure 1 a view partly in section of a 15 tooth root having my improved sheath mounted therein and shown in connection with a standard crown or facing.

Fig. 2 a similar view showing my improved sheath in connection with a root 20 having a standard cap and the crown or facing with a metallic base.

Fig. 3 a similar view showing a root provided with a standard cap with my improved sheath connected therewith in connection with a crown like that shown in 25 Fig. 1.

Fig. 4 a side view of my improved sheath, detached.

Fig. 5 a front view illustrating the application of my invention to bridge work.

This invention relates to an improvement in artificial denture, the object being to provide means for connecting crown or bridge work to roots of teeth in such a way that the 35 artificial teeth may be readily removed by the wearer for the purpose of cleaning or to permit of ready treatment of the roots should occasion require without cutting away the crown or facing, or breaking the 40 foundation for the post of a standard porcelain top or facing; and the invention consists in the construction hereinafter described and particularly recited in the claims.

In carrying out my invention I employ a 45 sheath 7 formed from gold or suitable material and adapted to be inserted into a tooth root 8. This sheath is formed at its upper end with a flange 9 and its lower end 10 is 50 open. Preferably and as herein shown the sheath will be formed with a swell or en-

largement near its upper end for the better engagement of the prongs 11 and 12 forming the post of a standard porcelain crown 13 which is usually provided in its under face 55 with a recess 15 which gives clearance for the flange 9 which stands above the upper edge of the root 8. Before the sheath is inserted into a tooth, a plug 16 of gutta percha or other suitable material will be inserted 60 into the bottom of the cavity and so as to close the inner end of the sheath, and through which access may be had to the root should it be necessary to treat the root which may thus be done without removing the 65 sheath. In many cases and as indicated in Figs. 2 and 3 of the drawings, a cap or facing plate 17 is placed over the top of the root 8, and instead of forming the tube integral with this cap I form the cap with a central opening 18 through which the sheath 70 may be inserted so that the flange 9 rests upon the upper edge of the cap, and if the porcelain crown 19 has a metal base 20 this base will be recessed to give clearance for 75 the flange or a porcelain crown 13 as shown in Figs. 1 and 3 of the drawings, may be used in connection with a cap or crown 17. In either case the sheath forms a bearing for 80 the crown and assists in holding the crown in position. In bridge work and as indicated in Fig. 5 of the drawings, two anchor roots 21 and 22 will have the sheaths mounted in them and so that if the end facings 23 and 24 are provided with pins these pins 85 may be inserted into the anchor teeth and the intermediate teeth 25 will be securely held in position and the entire bridge removed by the wearer when desired for 90 cleansing.

It will thus be seen that with my improved sheath, any of the standard crowns or facings may be employed, the sheath forming a suitable receptacle for the standard pins or pegs with which standard 95 crowns are provided.

I claim:—

1. A sheath for artificial denture comprising a tubular portion expanded near its upper end and formed at its upper end with an 100 annular flange.
2. The combination with a prepared root

formed with a cavity and provided with a cap formed with a central opening in line with the cavity, of a sheath inserted through said opening, said sheath formed with a flange resting upon the upper face of said cap.

In testimony whereof, I have signed this
